UNITED STATES PATENT OFFICE.

JOSEPH W. BALET, OF NEW YORK, N. Y., ASSIGNOR OF ONE-HALF TO ROBERT DUNLAP AND LUKE F. COZANS, OF SAME PLACE.

ELECTRIC-CURRENT REGULATOR.

SPECIFICATION forming part of Letters Patent No. 398,927, dated March 5, 1889.

Application filed May 14, 1888. Serial No. 273,841. (No model.)

To all whom it may concern:

Be it known that I, JOSEPH WILHELMUS BALET, of the city, county, and State of New York, have invented a new and Improved 5 Electric-Current Regulator, of which the following is a specification, reference being had to the annexed drawings, forming a part thereof, in which—

Figure 1 is a transverse section of the current-regulator, taken on line x x in Fig. 2. Fig. 2 is a plan view showing diagrammatically the motor used in connection with the regulator. Fig. 3 is a plan view showing how the electrical connections in a system are 15 made.

Similar letters and figures of reference indicate corresponding parts in both views.

The object of my invention is to provide a simple and efficient current-regulator for use 20 in connection with any electrical circuit, but more particularly designed for use in connection with storage-batteries.

My invention consists in a translating device formed of a helix and a pair of soft-iron 25 bars supported movably in the helix, each bar being connected with a switch-arm adapted to move between a pair of contacts connected with the circuit in which the helix is placed.

30 It also consists in the combination, with the translating device, of an electric motor having its field-magnet connected with the main circuit, so that the current may always flow in the same direction through the conductor 35 of the field-magnet, and having commutator-brushes connected with the contact-points of the translating device, so that the current may be sent in either direction through the armature of the motor, and thus enable the 40 motor to be used for operating switches in one direction or the other according to the requirements of the current being regulated, all as hereinafter more fully described.

The connections shown in Fig. 2 are intended 45 for very heavy currents. In Fig. 3 the connections are made in parallel with the lamps 21. I do, however, not limit myself to any connection, while same is made so as to satisfy the circumstances. The main difference between the two connections shown is

that in Fig. 2 the object is to get a constant electro-motive force, and in Fig. 3 to get a constant potential.

Upon the spool A, which is preferably of elliptical form, is wound a quantity of wire 55 forming a helix, B. In the center of the said spool A are supported frames formed of the bars a a' a^2 a^3 , the arms b b' , connecting the lower ends of the said bars, and the switch-arms c c' , connecting the upper ends of the 60 said bars and projecting over the face of the spool A. The bars a and a^2 , as well as the arms b b' c c' , are of non-magnetic material, while the bars a' a^3 are of soft iron. The arms b b' c c' are pivoted above and below 65 the spool A upon pivotal screws e , extending through brackets f , attached to the top and bottom of the spool A.

Upon the upper head, g , of the spool A are secured six binding-posts, 1 2 3 4 5 6. To the 70 binding-posts 5 6 are attached flat springs h h' , which bear upon the outer sides of the arms c c' , and the said springs and arms are oppositely arranged with respect to each other, the arm c projecting between the binding- 75 posts 1 2, and the arm c' projecting between the binding-posts 3 4. The binding-posts 1 2 3 4 are provided with contact-screws i , arranged in the paths of the said arms.

Arranged in this way the bars a' a^3 are supported parallel with each other within the center of the helix B, so that when a current is sent through the helix the bars are similarly magnetized and consequently repel each other. The repulsion of the bars a' a^3 is opposed by 85 the springs h h' , so that when the current passing through the helix produces a repulsion between the bars a' a^3 , which is equivalent to the pressure of the springs h h' , the arms c c' will take a central position between the 90 contact-screws i . When the current diminishes, the springs carry the arms c c' over toward the contact-screws i of the binding-posts 2 4. When the strength of the current increases, the repulsion of the bars a' a^3 moves 95 the arms c c' so that they are brought into contact with the screws i of the posts 1 3 against the pressure of the springs h h' .

The motor C, used in connection with my device, is of well-known construction, having 100

the field-magnet j and the armature k revolving between its poles, the current being supplied to the armature through the commutator-brushes $l' l$. The field-magnet j of the 5 motor C is connected with the main-circuit conductor D in the shunt. The binding-post 1 of the translating device is connected directly with the commutator-brush l of the motor. The binding-post 2 is connected with 10 the brush l' of the motor, and the binding-post 3 is connected with the commutator-brush l' . The binding-post 4 is connected with the brush l , and binding-posts 5 and 6 are connected with the main conductor D in a shunt around the field-magnet of the 15 motor C. One terminal of the helix B is connected with the main conductor outside of one of the connections of the field-magnet and binding-post 6. The other terminal 20 is connected with the main conductor within the shunt of the field-magnet of the motor. When the current flows in the direction indicated by the arrow through the main conductor, a portion of it passes through the helix B and magnetizes the bars $a' a^3$ more or less, according to the strength of the current. An 25 increase of magnetism causes the bars which are similarly magnetized to repel each other, and a diminution of the current diminishes the repulsive power of the bars $a' a^3$, when the springs $h h'$ preponderate, and cause the arms $c c'$ to move in the opposite direction; but when the current is normal the arms $c c'$ rest 30 in the central position between their respective contact-points, the current in the main conductor being normal and the arms $c c'$ occupying a central position, as described. The motor C remains quiescent and the switching devices to be controlled by the current-regulator remain unmoved. When the 35 strength of the current increases, the repulsion of the bars $a' a^3$ causes the arms $c c'$ to contact, respectively, with the screws i in the binding-posts 1 3. The current then flows 40 from the main conductor to the binding-post 6, through the spring h , the arm c' , binding-post 3, brush l' , armature k , brush l , thence to binding-post 1, arm c , spring h' , and binding-post 5 back to the main conductor, causing 45 the armature k to rotate in the direction required to change the position of the switches, so as to diminish the current in the main conductor. When the current becomes normal, the arms $c c'$ take a normal position. 50 When the current diminishes, the repulsion of the bars $a' a^3$ is diminished and the springs $h h'$ move the arms $c c'$, so as to bring them, respectively, into contact with the screws i of the binding-posts 2 4. The current from the 55 main conductor then flows to the binding-post 6, thence through the spring h , arm c' , binding-post 4, thence to the brush l , as indi- 60

cated by dotted lines, through the armature k , brush l' , thence to binding-post 2, as indicated by dotted lines, thence through the arm 65 c , spring h' , and binding-post 5 back to the main conductor, thus reversing the direction of the current through the armature k , and causing it to revolve in the opposite direction.

In Fig. 3, upon the shaft k' of the armature 70 k of the motor C, is attached the screw k^2 , which engages the wheel k^3 . Upon the shaft of said wheel is attached the switch-arm N, which is electrically connected with the conductor 24^a, and which will turn alternatively 75 over the contacts w . The dynamo is indicated by Y, and P represents accumulators or resistance-coils, and after the foregoing description it will readily be seen how the accumulators or resistance-coils P are shut in or 80 out of the circuit.

Having thus described my invention, I claim as new and desire to secure by Letters Patent

1. In an electric-current regulator, the combination, with a helix, of two switch-operating bars of magnetic material, each movably supported within the helix, substantially as described. 85

2. In an electric-current regulator, the combination of a helix, two bars of magnetic material arranged within the helix parallel to its axis, two arms attached to and movable by the bars, springs pressing the movable arms in opposition to the magnetic action of the 95 bars, and contact-points arranged to be touched by the movable arms, substantially as specified. 90

3. In an electric-current regulator, the combination of a helix, two bars of magnetic material arranged on pivotal supports and arranged to move independently of each other, two spring-pressed arms carried by the magnetic bars, contact-points arranged in the paths of the arms, an electric motor, and circuit-connections, the whole being arranged to cause the current to pass in one direction or in the other through the armature of the electric motor, according as the current is strong or weak, substantially as specified. 105

4. In a current-regulator, the combination of the helix B, magnetic bars $a' a^3$, arms $c c'$, connected with the bars, two pairs of contact-points, one pair for each arm $c c'$, the springs $h h'$, the electric motor C, having its field-magnet permanently connected in a shunt to the main circuit, and the double connections of the commutator-brushes $l' l$, substantially as specified. 110
